Attorney

UNITED STATES PATENT OFFICE

CHARLES A. HERR, OF CLAYTON, MISSOURI

DESIGN FOR A FOLDING ENVELOPE OR SIMILAR ARTICLE

Application filed December 30, 1931. Serial No. 42,300. Term of patent 14 years.

To all whom it may concern:

Be it known that I, CHARLES A. HERR, a citizen of the United States, residing in Clayton, in the county of St. Louis and State of Missouri, have invented a new, original, and ornamental Design for a Folding Envelope or Similar Article, of which the following is a specification, reference being had to the accompanying drawing, forming a part hereof, in which the figure is a face view of a newspaper wrapper showing my new design.

I also contemplate using this design in the form of folding envelopes, portfolios and similar articles of manufacture.

My design consists of three oblong panels, with projecting tabs at both ends of one of said panels, the outer surface of each panel disclosing a combination of solid straight lines running spacedly parallel with the long side of the panel and solid lines indented inwardly forming steps and becoming end sections to the panel.

I claim—

The ornamental design for a folding envelope or similar article, as shown and described.

In testimony whereof I affix my signature.
CHARLES A. HERR.
